UNITED STATES PATENT OFFICE.

CHARLES H. MORGAN, OF WORCESTER, MASSACHUSETTS.

GAS-ENGINE.

No. 864,249.

Specification of Letters Patent.

Patented Aug. 27, 1907.

Application filed May 16, 1900. Serial No. 16,844.

To all whom it may concern:

Be it known that I, CHARLES H. MORGAN, a citizen of the United States, and a resident of Worcester, in the county of Worcester and Commonwealth of Massachusetts, have invented certain new and useful Improvements in a Gas-Engine, of which the following is a specification, reference being had to the accompanying drawings, in which—

Figure 1 represents a side elevation of a gas engine embodying my invention. Fig. 2 is a plan view. Fig. 3 is a sectional view on line 3, 3, Fig. 2. Fig. 4 is a perspective view of the rocking shaft to which the pistons are coupled, and Fig. 5 is a detached view of one of the engine pistons represented in vertical, central, sectional view and showing the method of connecting the engine piston with the piston of the pumping cylinder placed in alinement with the engine cylinder.

Similar reference letters and figures refer to similar parts in the different views.

20 My invention relates to the class of engines known as single acting and it has for its objects to couple four or more cylinders in a single engine, whereby I increase the number of impulses during each revolution of the engine and also to render the engine more efficient in operation and compact in construction and I accomplish these objects by means of the construction and arrangement of parts as hereinafter described and set forth by the annexed claims.

Referring to the drawings which represent a gas engine embodying my invention, A denotes the base of the engine; B a crank shaft journaled thereon, provided at its center with a crank C and carrying upon one end a fly wheel D. Mounted upon the base A are the four cylinders E¹, E², E³, and E⁴, open at their lower ends and provided at their upper ends with the usual valve mechanism employed in engines of this class for the admission and exhaust of an explosive charge. The cylinders E¹, E², E³ and E⁴ contain pistons E Fig. 3 which are duplicates of each other, that 40 in cylinder E¹ being shown in section in Fig. 3.

Journaled in the base A is a rocking shaft G provided with a pair of radial arms G¹ on opposite sides of the shaft and having their ends extending beneath the open ends of the cylinders and connected by links H with the 45 pistons in each cylinder. Extending upwardly from the rocking shaft G and preferably midway between the radial arms G¹ is a stud arm I carrying a stud I¹ operatively connected with a crank pin C¹ by a connecting rod J, by which the rocking motion of the shaft G is made to impart a rotary motion to the crank shaft B.

The valve mechanism by which the operation of each of the engine pistons is controlled is of the usual and well known type now in use in gas engines and comprises admission and exhaust valves having stems K 55 which are depressed by means of the levers K¹, K². The levers K² are attached to rocking shafts L which

are journaled in brackets mounted upon the tops of the cylinders E¹, E² and the levers K² are attached to sleeves L¹ rocking on the shafts L. The shafts L and sleeves L¹ are provided with radial arms L², L³, which 60 are connected by connecting rods L⁴, L⁵ with bell cranks L⁶ which are pivoted upon brackets M and carry cam rolls N, which are actuated by the cams N² carried upon a shaft N² driven from the crank shaft B by means of the spur gears N³ and N⁴. The cams N² rock the 65 bell cranks L⁶ and impart a longitudinal thrusting motion to the connecting rods L⁴, L⁵, to depress the valve stems in the cylinders E¹ and E². In a similar manner the valve stems of the cylinders E³, E⁴ are depressed by levers O attached to rocking sleeves O¹ provided with 70 radial arms O² connected by rods O³ with bell crank levers O⁴ carrying cam rolls O⁵ which are actuated by the cams O⁶ on the cam shaft N², to impart a longitudinal thrusting motion to the connecting rods O³ to depress the valve stems in the cylinders E³ and E⁴. The 75 valve stems are lifted by springs, not shown, as is common in engines of this class, thereby reversing the bell cranks and holding their cam rolls against the periphery of the actuating cams.

The radial arms G¹ and stud arm I are preferably 80 formed integrally with the rocking shaft G and the pistons of the cylinders E¹, E², E³ and E⁴ are supported upon the free ends of the arms G¹ so that the pistons in the cylinders E¹, E², E³ and E⁴ move in unison; the pistons in one pair of cylinders ascending while 85 the pistons in the opposite pair of cylinders are descending, thereby allowing the charge to be ignited alternately in the cylinders of each pair; for example, the charge in cylinder E¹ being ignited and forcing its piston downwardly while the piston in cylinder E² 90 is receiving its charge ready to be compressed and ignited at its next upward movement, and similarly the charge is ignited alternately in the cylinders on the opposite side of the rocking shaft G, or in cylinders E³, E⁴, thus an impulse is given to the shaft G at each of its 95 rocking movements, imparting an impulse to the crank shaft twice during each complete oscillation of the rocking shaft G.

The stud arm I is placed in the center of the rocking shaft G and the cylinders E³, E⁴ can be placed in 100 close proximity to each other as space is only required between them for the connecting rod J and a distance is only required between the two rows of cylinders sufficient to allow for the vibratory movement of the stud arm I.

The crank shaft is journaled upon the short base A which requires but little floor space and is adapted to resist the strain of the operating parts. The only connection between the valve mechanism at the top of the cylinders and the operating cams consists in the bell 110 cranks and their connecting links which can be readily disconnected, freeing the cylinder heads and allowing

them and the valve mechanism contained therein to be removed from the cylinders. The rocking shaft G is hollow with its ends closed by caps P forming a concentric oil chamber P¹ in the rocking shaft, which 5 is supplied by a pipe P² leading to an oil reservoir P³ supported in a convenient elevated position. The pipe P² communicates with the oil chamber P¹ through a stuffing box P⁴ held concentrically in the end of the rocking shaft by which oil is supplied to the chamber P¹ under pressure due to the elevation of the reservoir P³. Radial holes are formed in the shaft G communicating with the oil chamber P¹ in which pipes P⁵ are inserted leading to the bearings in the outer ends of the radial arms G¹ and stud arm I; the oil being forced 10 through the pipes P⁵ by the pressure in the oil chamber P¹. The base A can be conveniently located over a pit Q, Fig. 3, in which can be placed pumping cylinders R, R, suspended by rods R¹ from the base in alignment with the engine cylinders and having their piston 15 rods S connected to the center of a yoke S¹, which is attached by rods S² with the engine pistons; the space between the rods S² furnishing room for the links H by which the engine pistons are connected with the radial arms G¹ of the rocking shaft G.

25 I have shown four cylinders mounted upon the base A with their pistons coupled to a common rocking shaft; but the number can be varied if desired.

What I claim as my invention and desire to secure by Letters Patent is:—

30 1. In a motor, the combination with a plurality of pairs of cylinders and pistons therein, of a walking beam located and extending between the opposite pairs of cylinders, the walking beam comprising a hollow shaft, a plurality of solid arms integral with the hollow shaft and 35 extending radially therefrom, the free ends of the arms being connected with the pistons whereby a rocking motion is imparted to the hollow shaft, the separate pairs of cylinders operating alternately, the cylinders in each

pair operating simultaneously, the individual arms connected with each pair of pistons being parallel with each other, the pairs of arms connected with one pair of pistons extending oppositely to the pair of arms connected with the opposite pair of pistons, and a stud arm formed integrally with the hollow shaft and extending radially therefrom at an angle to the directions in which the arms extend, the stud arm located at a point intermediate the oppositely extending pairs of arms, the free end of the stud arm connected with any driven mechanism. 40

2. The combination with a plurality of cylinders having pistons therein, of a hollow rock shaft extending between the cylinders and separating them into two equally divided series, a plurality of oppositely extending radial arms corresponding in number to the number of cylinders, the free ends of the arms provided with bearings for connection with the pistons, the arms extending on one side of the rock shaft being arranged parallel with each other, a stud arm formed integrally with the hollow shaft and extending radially therefrom at an angle with the arms and from a point on the shaft equidistant from the opposite outer series of arms, the free end of the stud arm provided with a bearing, a lubricant supply, a means for conveying the lubricant supply to the hollow shaft and a plurality of tubes connected with the hollow shaft and extending radially thereto and parallel and external to the radially arms and stud arm, the tubes connecting at their outer ends with the bearings in the free ends of the arms and stud arm. 50

3. In a motor, the combination with a plurality of cylinders having pistons therein, valve stems in said cylinders, of a rock shaft, a plurality of arms on the shaft, 55 said arms adapted to engage the pistons, a stud arm on the rock shaft, a crank shaft connected to the stud arm, an auxiliary shaft driven by the crank shaft, and means connecting the auxiliary shaft with the valve stems, whereby they are operated. 60

In testimony whereof I have signed my name to this specification in presence of two subscribing witnesses, this the seventh day of May, 1900.

CHAS. H. MORGAN.
